UNITED STATES PATENT OFFICE

FRANK J. GORIUP, OF MCKEES ROCKS, PENNSYLVANIA

DESIGN FOR A MINIATURE GREENHOUSE

Application filed March 5, 1932. Serial No. 43,094. Term of patent 7 years.

To all whom it may concern:

Be it known that I, FRANK J. GORIUP, a citizen of the United States of America, and residing in the borough of McKees Rocks, in the county of Allegheny and State of Pennsylvania, have invented a new, original, and ornamental Design for Miniature Greenhouse, of which the following is a specification, reference being had to the accompanying drawing, forming a part thereof.

In the drawing Fig. 1 is a perspective view of the miniature greenhouse. Fig. 2 is an end view of the same.

Fig. 3 is a detail showing of the novel design of the device in which *a* indicates bro-

ken lines that are made by painting or otherwise forming the design upon the surface of the glass. These lines present a series of formations around common points by the interruptions of the lines.

As best shown in Figure 3, each pane is provided with subdivisional markings *a* arranged to cause the single panes to appear as though composed of a multiplicity of small panes, these markings being made by painting or otherwise forming division marks on the surface of the glass.

I claim:

The ornamental design for a miniature greenhouse as shown and described.

FRANK J. GORIUP.
